UNITED STATES PATENT OFFICE.

JOHN D. JONES, OF NORTH TOPEKA, KANSAS.

SPLINT-CUTTING MACHINE.

SPECIFICATION forming part of Letters Patent No. 311,496, dated February 3, 1885.

Application filed June 19, 1884. (No model.)

To all whom it may concern:

Be it known that I, JOHN D. JONES, a citizen of the United States, residing at North Topeka, in the county of Shawnee and State of Kansas, have invented certain new and useful Improvements in Splint-Cutting Machines; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention relates to machines for cutting splints for matches or other uses; and it consists in the novel construction, combination, and arrangement of the several parts, as will be hereinafter more fully described and claimed.

20 In the drawings, Figure 1 is a perspective view of my machine. Fig. 2 is a vertical longitudinal section thereof. Fig. 3 is a detail view of the feed mechanism.

The supporting or main frame is composed 25 of two upright side plates, A A', formed, preferably, with flanged feet, as shown, to facilitate the fastening thereof to the bench or stand. The shaft b' is journaled in and extends between the upper ends of the plates, and is provided on one end with the power-pulleys B, and on the other with a balance or fly wheel, b². The eccentric b³ is formed on the middle of the shaft between the plates A A'. The plates A A' are provided near their front edges 30 with suitable guides for the cross-head C, which supports the cutting-knife c', and has the connecting rod or pitman b⁴ pivotally secured to its upper end, and said pitman is screw-threaded at its opposite end into the eccentric ring, so the length of the stroke may be 35 adjusted as desired. The cross-head C in operation reciprocates vertically in the guides of the framing, as will be understood. An arm, c², is fixed to the outer side of the cross-head, and projects laterally beyond the frame-plate A, for the purposes presently described. Rollers R R are journaled in the lower edge of the main frame, between the plates thereof, and two corrugated feed-rollers, D D', are journaled 40 one above the other near the outer end of the said frame, the lower roller, D', being in line with the anti-friction rollers R. The opposite

ends of these rollers D D' are journaled in yielding bearings D², (see Fig. 3,) cushioned by rubber or other suitable elastic substance, 55 so as to provide for slight variations in the thickness of the material m to be cut, the rollers D D' running on, respectively, the upper and lower sides of such material, as will be understood from Fig. 1. The journals of the 60 rollers D D' are extended beyond the side plate, A, and have secured thereon gears d d', meshed together, so said rollers will be concurrently actuated and revolved in opposite directions, in order to effect the forward feed- 65 ing of the material toward the cutter, in the manner presently more fully set forth. The extended journal of the roller D is also provided with a ratchet wheel or ring, d², which is engaged by the pallet, presently described, 70 for the purpose of actuating the feed-rollers D D'. A bar, E, is pivoted at its inner end to the side plate, A, and extends thence forward, and has its opposite end carried in advance of the said plate, in position to be engaged on its under side, and raised vertically by the arm c², 75 extended laterally from the cross-head, as before described. The arm E is formed with a horizontally-elongated slot, e, about midway its length, and is held at its outer end in a 80 suitable guide, E'. The base-bar E² of guide-frame E' has a set-screw, E³, turned vertically upward through it, and may be adjusted above the bar E² to any proper degree, in order to vary the distance to which the arm E can fall, 85 and thus regulate the feed of the machine, as will be understood from Fig. 3. The outer end of the arm E is given a downward tension, 90 preferably by means of a spring, e', as shown. This spring causes the downward movement 95 of the arm when released by the downward stroke of the cross-head. It will be understood that a weight could be used instead of spring e'; or the outer end of arm E could be so connected with arm c² of the cross-head that the latter will give the arm E a positive downward as well as upward movement; but I prefer to employ the construction shown, and before described. A pallet, F, has its upper end secured to arm E, preferably by means of a 100 bolt passed through the slot e, so the point of connection may be adjusted along arm E to vary the length of the stroke of the pallet. The lower end of this pallet is formed with a

clutch, f , adapted to engage the ratchet-wheel d^2 and revolve the same on the upstroke of the pallet. A stop-pawl, f' , is also pivoted to the pallet and engages with the ratchet d^2 , to hold the feed-rollers, and thereby the stock or series of ribbons, in position during the operation of cutting. It is manifest the location of this stop-pawl might be changed from the pallet to the frame-plate, or said pawl might be dispensed with, though I prefer to use it, as shown and described. A spring, F' , connects the pallet with the plate A , so as to hold the clutch f in engagement with the ratchet-ring d^2 , as will be understood from the references.

15 In the manufacture of my machine I construct the ratchet-ring and feed-rollers so the number of teeth in the former bear such a relation to the diameter of the feed-rollers $D D'$ that one tooth of the ratchet is equal the width 20 of the splint to be cut, measured on the circumference of the feed-rollers.

The material to be split into splints has first been cut into ribbons by the usual form of veneer-cutting, the grain of the wood running 25 parallel the width of the ribbons, and this width representing the length of the splints desired, as will be understood. A number of these ribbons are placed in the frame on the rollers $R R'$, and have their forward ends 30 brought between and held firmly by the feed-rollers $D D'$. Power is then applied to the drive-pulley and the shaft made to revolve, operating the eccentric, and causing the cross-head to reciprocate in its guides, cutting the 35 splints with each downstroke, and by means of the lateral arm thereof actuating the arm E and pallet F , engaged with the ratchet d^2 , and thus by the before-described mechanism the blanks are fed forward in position for a 40 new cut of splints, as will be appreciated.

By adjusting the connection of the pallet and its operating-arm the length of stroke of the pallet and the extent of revolution of the ratchet may be varied so as to increase or diminish 45 the width of the splints, as desired.

In Fig. 1 it will be seen the cross-head is shown at about its highest point and the bar E has been elevated by part c^2 . When the cross-head is forced downward, the bar E falls, bringing the point f in position to again engage the 50 teeth of ratchet d^2 .

In operation the bar E is always in contact with the part c^2 , and rests on said part, being raised thereby, and lowered when said part c^2 is lowered, as will be understood from the 55 drawings and foregoing description.

Having thus described my invention, what I claim, and desire to secure by Letters Patent, is—

1. The combination of the cross-head, 60 the feed-rollers both having intermeshed gears, and one of said rollers being provided with a ratchet-wheel, a pallet adapted at one end to engage the ratchet-wheel, and having its opposite end supported on the pivoted arm, 65 and the arm pivoted at one end, and having its other end operated by the cross-head, substantially as and for the purposes specified.

2. The combination of the feed-rollers having their journals or shafts provided with intermeshed gears, the ratchet-ring secured on one of said journals, the arm pivoted at one end and extended approximately horizontally along the framing, the cross-head provided within a bar or extension engaged with the 75 said arm, and a pallet depending from said arm and having a clutch adapted to engage and operate the ratchet-ring, all substantially as and for the purposes set forth.

3. The combination of the cross-head provided with lateral arm or extension c^2 , the feed-rollers having their journals extended, and provided with intermeshed gears, the ratchet-ring secured on one of said journals, the arm E , pivoted at its inner end, and having its opposite end extended in position to be engaged by the bar c^2 , the pendent pallet secured at its upper end to the pivoted arm, and having its opposite end adapted to engage the ratchet-ring, and the springs $e' F$, secured at one end to the framing a , and at their other end with, respectively, the pivoted arm and the pallet, substantially as set forth.

4. The combination of the feed-rollers, the ratchet-wheel secured on the shaft of one of said rollers, the pallet having its lower end adapted to engage the ratchet, and its other end connected with the pivoted arm, the arm having one end pivoted, and its other end held and movable vertically in the guide-frame, 100 and the set-screw turned upward through the base-bar of said frame, substantially as and for the purposes set forth.

In testimony whereof I affix my signature in presence of two witnesses.

JOHN D. JONES.
